Patented Aug. 6, 1963

195,827

CLOSURE HINGE

George W. Melcher, Bally, Pa., assignor to Bally Case
and Cooler, Inc., Bally, Pa.

Filed Dec. 14, 1962, Ser. No. 72,863

Term of patent 14 years

(Cl. D10—9)

FIG. 1

FIG. 2

FIG. 3

FIG. 4

FIG. 5

FIG. 6

FIG. 7

FIGURE 1 is a view in front elevation of the closure hinge embodying my new design.

FIGURE 2 is a view in side elevation thereof, looking from the left of FIGURE 1.

FIGURE 3 is a view in side elevation thereof, looking from the right of FIGURE 1.

FIGURE 4 is a top plan view thereof.

FIGURE 5 is a bottom view thereof.

FIGURE 6 is a rear view in elevation thereof, and

FIGURE 7 is a front view thereof with the hinge plate swung to a different position from that of FIGURE 1.

I claim:

The ornamental design for a closure hinge, as shown and described.
